UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

PUMPING MECHANISM.

Application filed June 22, 1923. Serial No. 647,090.

My invention relates to pumping mechanisms, and particularly to displacement pumping mechanisms.

An object of my invention is to provide an improved displacement pumping mechanism. Another object of my invention is to provide an improved displacement pumping mechanism whose component elements are especially convenient to assemble and disassemble and which take up a materially less over-all space so that it is, as a result, capable of being inserted in a well casing of smaller diameter. Other objects and disadvantages of my invention will hereinafter more fully appear.

In the accompanying drawings I have shown for purposes of illustration one form which my invention may assume in practice.

In these drawings,—

20 Fig. 1 is a diagrammatic view of one illustrative embodiment of my invention incorporated in a complete system.

25 Fig. 2 is a view, partially in elevation and partially in central vertical section, through one of the displacement tanks used as a unit in the system.

Fig. 3 is a transverse section on the line 3—3 of Fig. 2.

30 Fig. 4 is an enlarged detail sectional view of the bottom of the lowermost displacement tank.

In the illustrative embodiment of my invention I have shown the same incorporated in a displacement pumping system in which 35 a compressor 1 discharges by way of a pipe 2 to an automatically operating switch mechanism 3 which operates to alternately supply air to one or the other of lines 4 and 5, the mechanism 3 herein connecting the line 40 which is not being supplied with air to the suction side of the compressor through a line 6. It will be evident that the pipe 6 may be omitted and the fluid vented direct to atmosphere, if desired. The lines 4 and 5 are 45 adapted to supply pumping fluid to a series of displacement tanks arranged in series in a well which is shown at 7. The well is lined with a casing 8 and within it there are a plurality of serially arranged displacement tanks 9 of which three are shown herein, but of which an even number will be used in practice, so that two equal series may be had. The first and other odd numbered tanks, counting from the top, are connected

with the pipe line 4, while the second and other even numbered tanks will be connected with the pipe line 5 in such manner that the odd numbered tanks may be vented so that they may fill while the even numbered tanks are discharging and vice versa. The tanks 55 60 are generally the same in construction with the exception of the bottom tank whose difference will be briefly described hereafter.

In Fig. 2 will be observed one of the tanks, say the top tank. This tank comprises a cylindrical body member 10 threaded at its opposite ends as at 11 and 12, the top end having threadedly engaged with the threaded portion 11 an end closure member 13 which is traversed by three holes, one of 70 these, 14, being coaxial with the axis of the cylinder 10 and having portions of different diameters, being of smaller diameter at the side adjacent the interior of the tank and of larger diameter thereabove. Threaded into the opening 15 which constitutes the smaller diameter portion of hole 14 is a pipe 16 extending substantially to the bottom of the section 10 where it carries threadedly secured thereto a valve cage member 17 whose bottom is closed by a perforated valve seat member 18, which affords a seat for a ball 75 check valve 19. It will be noted that the valve cage member 17 is of such length that the lower end thereof and particularly the 80 seat member 18 projects beyond the end of the cylinder member 10 in such manner that by removing the lower closure member of the cylinder member 10 (which will shortly be described) access may be had readily to 85 the ball check valve and the seat thereof for the purpose of permitting cleaning thereof, etc. The upper, or larger diametered portion 21, of the opening 14, has threaded thereinto a pipe 22 which constitutes the 90 connection between the tank and the bottom of the next adjacent higher tank, the connection between the member 22 and the tank next above being the same as the connection of the corresponding member 22' 95 from the next lower tank with the bottom of the tank shown in Fig. 2. The member 13 is traversed by a hole of uniform diameter 24 through which the pipe 5 extends without interruption to the tank next below. The member 13 is finally traversed by a further hole 26, the disposition and the diameter of which are such that it overlaps and 100 105

opens into a recess 27 which is threaded for the reception of the threads 11 at the top of the member 10 and overlies and communicates with a port or opening 28 which is displaced laterally from the recess 26 and which in connection with the opening 28 constitutes an opening extending completely through the full thickness of the member 13. It will be noted that into the opening 28 there is 10 threaded a pipe member 29 which extends through an opening; not shown in the drawings but corresponding to the opening 24, in the top head of the next lower tank. Into the top of the opening 26 there is threaded a 15 closure member 30 which carries a pipe connection 31 with the line 4. The lower end of the displacement tank is constituted by a member 32 which has a bore 33 formed therein and which is threaded to receive the 20 lower end of the pipe section 10, it being noted as pointed out above that, when the member 32 is removed, free access may be had to the standing or check valve member 19 and its seat member 18, the member 32 being 25 recessed for a substantial distance to permit the valve casing 17 to project into it. The member 32 is traversed by a threaded opening 34 into which the pipe 22' (referred to above) is threaded. The member 30 30 is also traversed by two other holes, one of which is shown in Fig. 2 at 36, and through this hole the pipe portion 29 extends in passing to the second lower tank. The other opening (not shown) permits the pipe 35 line 5 to pass through it on its way to the next lower tank.

With regard to the bottom tank, it is of the same general construction as all the other tanks described except for the fact that it 40 comprises an additional check valve. The bottom closure member of the bottom tank is of built-up construction and is designated 40 and is threaded on to the pipe section 10' which constitutes the body of the lowermost 45 tank. The member 40 has threaded thereinto an annular valve guiding portion 41 having wings 42 so arranged as to properly center a check valve 43, the wings having projections 44 extending inwardly at their 50 top to prevent the valve moving too far off its seat and the member 41 being bored with an opening through its bottom for the full diameter of the check valve 43. Threaded into the bottom of the member 40 is a valve 55 seat member 45 providing a valve seat 46 with which the valve 43 is adapted to cooperate, this member being screwed home into close contact with the bottom of the member 41. As a result it will be evident that 60 the valve will be smoothly guided and yet prevented by the members 41 and 45 from possibly escaping from its position.

The general mode of operation of this system will be readily understood. The bottom tank will fill with liquid due to the head

of water in the well and this charge will be progressively pumped up through the various higher chambers, it being understood, of course, that the entire set of chambers, however, are working at the same time, half of them being filling and half of them emptying. By reason of the arrangement of the parts going to make up the displacement chambers it will be clear that a tank of maximum volume may be used and that the entire set of displacement chambers or tanks may be accurately centered in the casing 8, it being further apparent that without any awkward projections or anything of that variety the air supply lines are adequately 80 protected from possible damage in inserting and withdrawing the parts of the pumping system for the well and the whole system is secured together. Of particular advantage is the avoidance of any but vertical joints. 85

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a displacement pumping mechanism, a displacement tank comprising a body member, top and bottom members, a discharge member supported by said top member, and a valve mechanism for controlling the same supported thereby and freely projecting beyond the bottom of said body member.
2. In a displacement pumping mechanism, a displacement tank comprising a body member, recessed top and bottom members into which said body member projects when said tank is assembled, and a discharge member supported by said top member and a valve mechanism for controlling fluid flow through the same supported thereby and freely projecting beyond the bottom of said body member into the recess in said bottom member.
3. In a displacement pumping mechanism, a displacement tank comprising a body member having top and bottom members, a discharge member supported by said top member, and a valve mechanism supported by said discharge member and extending into said bottom member, said valve mechanism preventing back flow through said discharge member and always being in communication with the tank interior.

4. In a displacement pumping mechanism, a displacement tank comprising a body member, recessed top and bottom members into which said body member projects when said tank is assembled, and a check valve controlled discharge member supported by said

top member and projecting beyond the bottom of said body member into the recess in said bottom member and comprising a check valve casing accessible upon removal of said bottom member.

5. In a displacement pumping mechanism, a displacement tank comprising a body member, recessed top and bottom members into which said body member projects when 10 said tank is assembled, and a check valve controlled discharge member supported by said top member and projecting beyond the bottom of said body member into the recess in said bottom member and comprising a 15 check valve casing having a removable valve seat portion accessible upon removal of said bottom member.

6. In a displacement pumping mechanism, a displacement tank comprising a body 20 member, a bottom member, and a top member, the latter having a plurality of recesses formed in one side thereof and having a cylindrical opening extending inwardly from the opposite side thereof and overlapping one of said recesses to permit communication therewith.

7. In a displacement pumping mechanism, a displacement tank comprising a body member, a bottom member, and a top member, 30 said top member having a cylindrical recess into which said body member projects, a cylindrical recess into which a pumping fluid line to a lower tank may be screwed, and an opening through its top, cylindrical 35 and cutting into both of said recesses, said last mentioned recess receiving a pumping fluid supply connection.

8. In a displacement pumping mechanism, a displacement tank comprising a top member, 40 a body member, and a composite bottom member including a valve seat member and a valve guide member, one of said two last mentioned members being disposed below the other and adapted to influence the 45 operative position thereof.

9. In a pumping mechanism, a fluid conducting member comprising a body member and a composite bottom member including a valve seat and guiding members, one of said 50 two last mentioned members being disposed below the other, and means for supporting the lowermost one independently of said other member.

10. In a pumping mechanism, fluid 55 conducting means comprising a body portion and a composite bottom including a valve seat member and guiding members, and means for supporting each of said members substantially independently of each other.

60 11. In a pumping mechanism, fluid conducting means comprising a body portion and a composite bottom, valve means including a plurality of cylindrical elements of substantially the same diameter and one of 65 which is disposed below the other, and

means for supporting the lowermost member independently of the other.

12. In a displacement pumping mechanism, a displacement tank comprising a body member and a composite bottom member 70 comprising a member adapted to threadedly engage the bottom of the body member, and valve seat and guiding members each having threaded engagement with said body engaging member.

75 13. In a displacement pumping mechanism, a displacement tank comprising a top member, a body member, and a composite bottom member comprising a member adapted to threadedly engage the bottom of the 80 body member, a valve guide member threaded into the fourth mentioned member and adapted to abut the bottom of the body member, and a valve seat member threaded into the fourth mentioned member and adapted 85 to abut the valve guide member.

14. A check valve comprising a casing member, a seat member secured in said casing member, a valve member, and a combined guide and retainer member having 90 guiding flanges with inwardly directed top portions and secured above said seat member and in contact with the latter in said casing member.

95 15. A fluid conducting member having a plurality of overlapping substantially cylindrical recesses, the overlying portions of which allow communication between the same.

100 16. A fluid conducting member comprising a plurality of substantially cylindrical recesses disposed on opposite sides thereof, the overlying portions of said recesses allowing communication therebetween.

105 17. A fluid conducting member comprising a substantially cylindrical element having a plurality of eccentrically disposed substantially cylindrical overlapping recesses.

110 18. A fluid conducting member comprising a plurality of cylindrical recesses and a third cylindrical recess overlapping one of said other recesses, communication between which is effected through said overlapping portion.

115 19. A fluid conducting member comprising an element having a plurality of cylindrical recesses and a third recess overlapping one and overlying the other of the same and communication therebetween being effected through the overlapping and overlying portions.

120 20. A fluid conducting member comprising an element having coaxial cylindrical openings and opposed openings, one of the latter openings being adapted to overlap one 125 of said coaxial openings.

125 21. A fluid conducting member comprising an element having coaxial cylindrical openings and opposed openings, one of the latter openings being adapted to overlap one 130 of said coaxial openings.

of said coaxial openings, and each of said openings being adapted to threadedly receive a fluid conducting member.

22. In a pumping system having a displacement tank comprising a body portion and top and bottom members, a fluid conducting pipe supported by and depending from said top member, and a valve mechanism entirely supported by said pipe and so positioned that it projects below the end of

23. In a pumping mechanism, a displacement tank having a body portion, top and bottom members, the latter of which has a recess, and a complete valve mechanism extending down into said recess beyond the end of said body portion and adapted to remain in said position when said bottom member is removed.

15
In testimony whereof I affix my signature.

JOHN OLIPHANT.

Certificate of Correction.

It is hereby certified that in Letters Patent No. 1,604,420, granted October 26, 1926, upon the application of John Oliphant, of Chicago, Illinois, for an improvement in "Pumping Mechanisms," errors appear in the printed specification requiring correction as follows: Page 3, line 97, claim 15, and line 103, claim 16, for the word "overlying" read *overlapping*; and that the said Letters Patent should be read with these corrections therein that the same may conform to the record of the case in the Patent Office.

Signed and sealed this 14th day of December, A. D. 1926.

[**SEAL.**]

M. J. MOORE,
Acting Commissioner of Patents.

CERTIFICATE OF CORRECTION.

Patent No. 1,604,420.

Granted October 26, 1926, to

JOHN OLIPHANT

It is hereby certified that error appears in the printed specification of the above numbered patent requiring correction as follows: Page 1, lines 13 and 14, for the word "disadvantages" read "advantages"; and that the said Letters Patent should be read with this correction therein that the same may conform to the record of the case in the Patent Office.

Signed and sealed this 7th day of June, A. D. 1927.

**M. J. Moore,
Acting Commissioner of Patents.**

Seal.
